Letters Patent No. 2464. Dated Sept. 25. 1866.

Design for a Candy Figure

The Schedule referred to in this Letters Patent and making part of the same

Is all where it may concern.

Be it known that I, Georhard Schultze of the city of Philadelphia and State of Pennsylvania, have invented and designed a new Figure for casting in Candy, of which the following is a full and exact description, reference being had to the accompanying photograph, making part of this Specification.

The Design relates to that class of Figures which are cast pillars of transparent or opaque candy, and are extensively used as tops for ornamenting Christmas trees etc. They are made by pouring the heated liquid Candy into a metallic mould; after that portion of the Candy which comes in contact with the mould, has crystallized and hardened to form a shell of sufficient strength, the inner, yet liquid portion is poured out again and the hollow casting is then removed from the mould and to this end is arranged to separate in two or more parts.

The figure represents a Steam Engine, the general shape and details of configuration being fully shown in the accompanying photograph.

What I claim as my invention, and desire to secure by Letters Patent, is
The Design for a Candy Figure herein set forth.

Witnessed

Theodore Berger,
Chas. E. Pandast.
